UNITED STATES PATENT OFFICE.

LYNN EDWIN HILL, OF NORTHFIELD, VERMONT, ASSIGNOR TO CROSS BROS. CO., OF NORTHFIELD, VERMONT, A CORPORATION OF VERMONT.

DESIGN FOR A MONUMENT DIE.

Application filed September 30, 1926. Serial No. 19,205. Term of patent 7 years.

To all whom it may concern:

Be it known that I, LYNN EDWIN HILL, a citizen of the United States, and a resident of Northfield, in the county of Washington and State of Vermont, have invented a new, original, and ornamental Design for Monument Die, of which the following is a specification, reference being had to the accompanying drawing, forming part thereof.

The figure is a perspective view of a monument die, showing my new design.

A dominant feature of the design resides in squared columns at the ends shorter than the height at the center of the die and offset therefrom with a flare at the bottom.

I claim:

The ornamental design for a monument die, substantially as shown and described.

LYNN EDWIN HILL.
